[57] CLAIM

The ornamental design for a name plate holder, as shown and described.

DESCRIPTION

FIG. 1 is a first side elevational view of a name plate holder showing my new design;

FIG. 2 is a front elevational view thereof;

FIG. 3 is a second side elevational view thereof;

FIG. 4 is a rear elevational view thereof;

FIG. 5 is a top plan view thereof;

FIG. 6 is a bottom plan view thereof;

FIG. 7 is a front perspective view thereof; and,

FIG. 8 is a perspective view thereof, with the broken lines shown for illustrative purposes only and forming no part of the claimed design.

FIG. 1

FIG. 2

FIG. 3

FIG. 4

FIG. 5

FIG. 6

FIG. 7

FIG. 8
